UNITED STATES PATENT OFFICE.

CHARLES A. RHOADES, OF PAMPA, TEXAS.

ROTARY ENGINE.

1,096,862.

Specification of Letters Patent.

Patented May 19, 1914.

Application filed July 27, 1912. Serial No. 711,869.

To all whom it may concern:

Be it known that I, CHARLES A. RHOADES, a citizen of the United States, residing at Pampa, in the county of Gray and State of 5 Texas, have invented certain new and useful Improvements in Rotary Engines, of which the following is a specification.

My invention relates to rotary engines in which any type of motive fluid can be used, 10 but particularly adapted for use with steam.

One object of my invention is to provide a rotary engine in which the rotor casing and rotor are independently supported each with relation to the other, and in this connection 15 to provide means for adjusting the rotor casing vertically in a frame so as to center the shaft with relation to the rotor casing and take off wear from the walls of the shaft opening.

20 A further object is to provide a rotor casing, one-half of which forms a live steam chest wherein the motive fluid is confined behind the blades of the rotor, the cross sectional area of the remainder of the casing being greater than the facial area of the blades 25 whereby to form an exhaust chamber into which the fluid passes from the live steam space and by which back pressure is greatly reduced.

30 Other objects will appear in the course of the following description.

My invention is illustrated in the accompanying drawings wherein:

Figure 1 is a perspective view of a rotary 35 engine constructed in accordance with my invention. Fig. 2 is a face view thereof. Fig. 3 is a vertical section on the line 3—3 of Fig. 2. Fig. 4 is a perspective view of one portion of the rotor casing.

40 Corresponding and like parts are referred to in the following description and indicated in all the views of the accompanying drawings by the same reference characters.

Referring to the drawings, 2 designates 45 one section of the casing of a rotary engine and 3 designates a complementary section designed to fit upon and cover the section 2, these sections 2 and 3 together inclosing a rotor space within which the rotor 5 is disposed. This rotor space is circular in form as is the rotor 5 and passing through the center of the rotor space is a shaft 6 upon which the rotor 5 is mounted to turn.

50 The rotor 5 comprises a circular body portion having radially disposed recesses in its

periphery within which the blades 7 are carried. These blades are narrower than the width of the rotor as illustrated in Fig. 3 and are forced outward and against the outer wall of the rotor casing by means of 60 springs 8 which are mounted in the bottom of the recess. Preferably these blades move on pins 9 projecting from the bottom of each recess.

The upper portion of the casing 2 supports 65 a valve chamber 10. The space 4 extends upward as at 11, the walls being gradually contracted, this space 11 being provided to accommodate a pivoted abutment 12. This abutment is triangular in form and is 70 mounted upon a rock shaft 13 projecting through the walls of the casing. The lower face of the abutment is concavely curved so that when the abutment is turned in one direction or the other, the curvature of the 75 under face will merge gradually into the curvature of the face of the piston space as illustrated in Fig. 2. The abutment is of such size that it may be rotated to a small extent within the space 11 so as to bring one 80 or the other horn of the abutment into contact with one or the other side of the space 11, depending upon the direction in which the rotor is moving. Thus if the rotor is to move in a counter-clockwise direction, the 85 abutment is turned as illustrated in Fig. 2 so as to leave a steam inlet designated 14 on one side, the under face of the abutment acting to depress the blades 7 against the force of the springs 8 so as to permit the blade to 90 pass the end of the abutment. As soon as a blade has passed the end of the abutment, it springs outward into contact with the inner face of the circumferential wall of the casing 2.

95 The valve chamber 10 is connected by means of a duct 15 with the space 11 as illustrated in Fig. 3 and this valve chamber at its forward end is connected in turn by a duct 16 with any suitable source of steam. Disposed within the valve chamber are valves whereby the inflow of steam to the rotor casing may be regulated. One of these valves is designated 17 and is mounted to rotate upon a shaft 18 passing through the valve chamber and geared to the rotor as will be later described. This valve 17 is provided with ports 19 which are adapted to register with the port of the duct 15 so that as the valve 17 rotates, the duct will be intermittently con- 100 105 110

nected with the space 10 so that steam will be intermittently admitted to the steam space of the engine.

Surrounding the shaft 18 is a sleeve 20 which extends out through the front wall of the engine casing and carries at its inner end a rotary valve disk 21 having a perforation 21^a having the same area and form as the perforations 19. This valve 21 is a steam regulating valve and acts to regulate the amount of steam which enters the engine while the valve 17 is a cut-off valve. The valve 20 carries at its end a handle 22 whereby the valve 21 may be manipulated.

15 The shaft 18 carries at its end the gear wheel 23 which meshes with a gear wheel 24 carried on a stub shaft 25 and this gear in turn meshes with a gear 26 carried upon one end of the shaft 6. Thus power is transmitted from the shaft 6 to the shaft 18 so as to rotate the valve 19 in time with the rotations of the rotor.

20 The abutment 12 is a reversing abutment, that is, the position of the abutment determines whether the rotor is to move in one direction or the other and for the purpose of manipulating the abutment to change the direction of movement of the engine, the abutment is carried upon a shaft 13 which 25 projects out through the face of the casing and is provided with a handle 27. By shifting this handle through an arc of a circle in one direction or the other, the abutment may be shifted from the position shown in 30 Fig. 2 to an oppositely disposed position where the opposite horn of the triangular abutment valve will extend downward toward the face of the rotor and the other horn be raised so as to shut off the steam 35 space and direct the steam in the opposite direction to that in Fig. 2.

35 It is to be particularly noted that while the upper portion of the rotor space 4 has a width equal to the width of the blades 7, the lower portion of the rotor space has a 40 width greater than the blades 7 and equal to the width of the body of the rotor. The purpose of this is to provide an exhaust space designated 28 whose cross section shall 45 be greater in area than the facial area of the blades 7, and to provide a live steam space designated 29 whose cross sectional area shall be the same as the facial area of the blades. Thus as a blade passes the abutment 12, the steam will issue behind the blade and force it forward, no steam being 50 permitted to pass around the blade but being held between the two walls of the casing, the periphery of the rotor body, the 55 outer wall of the casing and the blade. As soon, however, as the blade has passed into the exhaust space 28 which, as before stated, has a cross sectional area greater than the 60 facial area of the blade, the steam can pass 65 around the edges of the blade and pass out

of an exhaust opening 30 formed in the lower portion of the rotor casing and connected to an exhaust pipe 31. In order to provide the live steam space before referred to, the lower portion of the casing is formed 70 wider below a horizontal line cutting through the axis of the rotor than the upper portion of the casing so that as each blade passes into this widened portion, the steam heretofore confined behind the blade can 75 escape around the side edges of the blade and have free passage to the exhaust opening 30. By this provision back pressure is 80 materially reduced. This tends also to reduce wear on the shaft caused by the back pressure of the exhaust.

85 Referring now to Fig. 1, it will be seen that the rotor casing is supported in a frame comprising a base 32 having uprights 33 and 34, the uprights 33 being spaced from 85 the uprights 34 so as to permit the rotor frame to slide vertically in the guides formed by these spaced uprights. The rotor casing is also provided with oppositely disposed outstanding vertical guide lugs 35 which hold the rotor casing from any turning movement. At the same time the rotor casing may be easily moved up or down within the guides formed by the standards 33 and 34. The standards 33 and 34 are 90 provided with the transversely extending supporting beams 36 each formed at its middle with a journal box 37 of any suitable character through which the shaft 6 projects. Thus the rotor is supported by the 95 shaft 6 upon the cross beams 36.

100 In order to support the casing of the rotor, I provide a plurality of jack screws designated 38 which extend upward from the base 32 and engage the rotor casing. I 105 have illustrated for this purpose four jack screws 38 arranged in pairs but I do not wish to be limited to the use of jack screws for this purpose nor to this arrangement. By turning the jack screws in one direction, 110 the rotor casing may be vertically adjusted so that the weight of the casing is not borne upon the shaft 6 and so that the shaft 6 may be supported entirely independently of the rotor casing. It will be seen that by this 115 arrangement the necessity of packing rings is eliminated as the wear upon the casing can be adjusted by the set screws. If there is any wear in either of the main boxes 37, the casing will give to it. If the shaft ran in boxes in the rotor casing and either of these boxes should wear, it would cause a 120 great friction in the cylinder and a leakage of steam. By constructing the engine as heretofore described, this leakage is reduced. 125

What I claim is:

1. A rotary engine including a rotor casing, a shaft passing therethrough, a rotor thereon, bearings supporting the rotor shaft, and spaced adjusting screws disposed on 130

each side of the central vertical plane of the casing engaging the rotor casing for vertical movement whereby the rotor casing may be independently adjusted relative to the 5 shaft.

2. A rotary engine including a rotor casing, a shaft passing therethrough, a rotor thereon, spaced standards forming guides between which the rotor casing is mounted 10 for vertical movement, and means for vertically raising or lowering the rotor casing between said guides, said means being disposed on each side of the middle vertical plane of the casing.

15 3. A rotary engine including a base, opposed pairs of spaced standards mounted upon the base, a rotor casing extending at opposite points of its diameter through the 20 space between the standards and having vertical guides engaging said standards, means disposed below the casing for raising or lowering it, transverse beams mounted upon the standards, journal boxes on said beams, and a rotor shaft passing through the 25 casing and mounted in said journal boxes.

4. In a rotary engine, a rotor having a circular body portion and radially projecting blades, and a rotor casing inclosing said rotor, one portion of the rotor casing being 30 contracted to the width of the blades so as

to form a live fluid space, the other portion of the rotor casing being transversely wider than the blades so as to form an exhaust space, said casing being formed with a motive fluid inlet opening into the live fluid 35 space and an exhaust opening from the exhaust port opening in the exhaust space.

5. In a rotary engine, a rotor having a body and outwardly moving spring pressed radial blades, said blades being less in width 40 than the width of the rotor body, and a rotor casing inclosing said rotor, the inner face of the casing being concentric to the axis of the rotor, the upper portion of the casing being contracted in width to the width of 45 the rotor blades while the lower portion of the casing is transversely greater in width than the rotor blades but less in width than the body of the rotor so as to provide an exhaust space, the casing being formed with 50 an inlet port opening into the live fluid space and an exhaust port opening from the exhaust space at the middle thereof.

In testimony whereof I affix my signature in presence of two witnesses.

CHARLES A. RHOADES. [L. s.]
